UNITED STATES PATENT OFFICE.

DANIEL A. HEGARTY, OF HOUSTON, TEXAS, ASSIGNOR TO MYSTIC WASHER COMPANY, OF HOUSTON, TEXAS.

SPRAY HEAD FOR BOILER-WASHING MACHINE.

Application filed September 27, 1926. Serial No. 137,937.

My invention relates to wash boilers in which boiling water is circulated in the machine for spraying upon the clothes which are to be washed.

5 In the use of wash boilers, the efficiency of the machine depends largely upon the force with which the boiling water is projected upon the clothes to be washed and also upon the saving of the energy of the 10 steam within the boiler so that it may be employed effectively in circulating the water against and through the articles in the wash.

It is an object of the invention to provide 15 a spray head for the water and steam, which is employed in cleaning the clothes, which will conserve the heat within the boiler so that the operation of the device may be accelerated and the time consumed in bringing the machine into operation may be reduced to a minimum.

20 It is also desired that the openings through which the boiling water is projected upon the clothes in the wash be formed in such manner as to prevent the clogging 25 thereof and with which the pressure valve may cooperate to free the openings of coagulated material.

Further objects and advantages of the 30 machine will more clearly appear in the more detailed description which follows:

Referring to the drawing herewith, Fig. 1 is a central vertical section through a wash boiler equipped with my improved spray head. Fig. 2 is a central vertical section of 35 the spray head on an enlarged scale showing one embodiment of the valve which may be employed therewith. Fig. 3 is a bottom plan view of the spray head shown in Fig. 2. Figs. 4 and 5 are sections similar to that 40 shown in Fig. 2, each illustrating a slightly different embodiment of the invention from that disclosed in Fig. 2. Like numerals of reference are employed to designate like parts in all the views.

45 In carrying out my invention, it is to be understood that the spray head may be adapted for use in various forms of clothes washing machines. I have illustrated it, however, as applied to a boiler of generally 50 circular shape, the sides 1 of which are flared toward the upper end. A cover 2 is provided adapted to fit tightly over the upper end of the container and a handle 3, preferably of some poor heat conducting material, is 55 shown through which the cover may be ma-

nipulated. A lateral tap or faucet 4 at the lower end allows the draining of the water from the container.

Within the container and resting on the bottom thereof is a conical pressure chamber 5. The outer edge of this chamber is turned downwardly to fit loosely against the walls of the container, and spaced openings 6 at the lower edge allows the circulation of liquid inwardly around the outer side and upwardly within the chamber. The upper end of the pressure chambers terminates in a nipple 7 which extends above the level of the chamber and provides an attachment for the circulating column 8. 60

The column 8 is a tubular member tapered from its lower toward its upper end and providing through its converging walls a passage in which the rate of flow of the liquid therein may be increased toward the 65 upper end. Below the circulating column I show a false bottom 9 fitting closely about the nipple 7 on the pressure chamber and supported centrally thereon. Its outer margin is supported by brackets 10 arranged 70 upon the side of the container. This bottom is perforated to allow the free circulation therethrough of the liquid. It serves as a support for the clothes and prevents them from coming into contact with the bottom 75 of the boiler to prevent accidental burning.

At the upper end of the circulating column 8 is the spray head having a lower neck 11 telescoping over the upper end of the circulating column. The spray head flares outwardly above the neck 11 to form the spray wall 12. Above this flaring wall the spray member is extended to provide a cylindrical portion 13 adapted to receive a cover 14 which may be held frictionally in place by 80 close contact with the wall 13 or may be retained in position in any desired manner. 85

At the upper end of the neck 11 a seat 15 is provided in which a valve member 16 may seat. Above this seat the wall 12 is 100 perforated to allow the water to be sprayed therefrom over the clothes. The spray openings which I employ are shown at 17, and it will be noted that said openings comprise slots arranged concentrically around the 105 wall 12 and allow the water to be sprayed therethrough in sheets over the clothes. This type of opening is particularly desirable from the fact that it may be made narrow so that the force of the water will carry 110

any obstruction, such as soap or coagulated material, in the water through the openings. Should any portion of the slot be filled up with material, however, there is still sufficient opening remaining to provide an outlet for the liquid.

Furthermore, the use of the valve 16 within the spray head causes a contact of the valve with the inner wall of the head. The 10 pressure of the steam and the ebullition of the water causes the valve to be agitated within the head so that it contacts repeatedly with the inner wall of the spray area, thus tending to assist in removing materials tending 15 to close the openings 17.

In Fig. 2, I have shown a ball valve closing the lower end of the spray head. This type of valve has the advantage of closing the upper end of the column 8 so that the heat from 20 the water in the pressure chamber 5 will not be allowed to escape into the upper part of the boiler and will act to accelerate the heating of the water to the boiling temperature to a marked extent. When the pressure of 25 the water in the pressure chamber and the column 8 has become great enough to lift the valve 16 from its position at the lower end of the spray head, the steam will cause the water to be projected with some force 30 through the openings 17 and the washing may thus be initiated some minutes in advance of the time which would ordinarily be consumed if the valve was not employed.

In Fig. 4, the valve 16' is made in the 35 shape of an inverted cone, the apex of which is rounded off, as shown at 18. The conical side walls, therefore, interfit closely with the inner wall 12 of the spray head and effectively close all of these openings. The upper 40 wall of the valve member 16' may be curved upwardly, as shown at 19. As will be noted, the valve members are made of hollow sheet metal and are therefore comparatively light, but they will resist the escape of heat from 45 the column 8 until the steam pressure has accumulated sufficiently to raise them from closed position. The action of the valve 16' will be slightly different from that of the valve 16, due to the fact that the outer wall 50 of the valve 16' will form a constricted passage for the boiling water and will serve more effectively to form a pressure chamber in which the steam will project the boiling water with force in a downwardly inclined 55 direction against the clothes in the boiler.

In Fig. 5, the valve 16'' is modified slightly over the construction shown in Fig. 4, in that the side walls of the valve are curved inwardly away from the wall 12 of the pressure chamber, the upper end being, however, flared outwardly to contact at 20 with the upper edge of the wall 12. In the use of this device, the raising of the valve 16'' will 60 allow the boiling liquid to enter more readily into the spray head and find an exit through

the slotted openings 17. The wall of the valve will act to deflect the water toward the openings and will have the effect of producing a spray of some force from the openings.

The employment of a spray head of the type here shown and described will enable the operator of the washer to bring the water to a boiling temperature and to hence bring the spraying of the boiling water into action appreciably quicker in point of time than could possibly be done without the use of the valve member employed. Not only is there a saving in time but the use of the valve serves to direct the boiling water laterally from the 70 openings in a most effective manner. Furthermore, the use of the valve contacting with the inner walls of the spray head, particularly the ball-shaped valve shown in Fig. 4, will assist in keeping the openings free of 75 material otherwise tending to clog them and prevent their spraying action. The further advantages of this invention will be apparent 80 to those skilled in the art.

What I claim as new and desire to protect 90 by Letters Patent is:

1. In a wash boiler a container, a pressure chamber therein, a circulating column thereon, a spray head on said column comprising an outwardly flaring wall having slotted 95 openings therein, a closure for the upper end of said head, and means within said head to assist said wash water in clearing said openings of material.

2. In a wash boiler a container, a pressure chamber therein, a circulating column thereon, a spray head on said column comprising an outwardly flaring wall having slotted 105 openings therein, a closure for the upper end of said head, and a valve in said head tending to close said head against the escape of fluid, and adapted to be moved by the fluid pressure to contact with the sides of said head, for the purpose described.

3. In a wash boiler a container, a pressure chamber therein, an upwardly tapered circulating column on said chamber, an outwardly flaring spray head thereon having slotted 115 openings in its side walls, and means acting to normally close the upper end of said column, but movable by fluid pressure to form a baffle to direct fluid toward said openings.

4. In a wash boiler a container, a pressure chamber therein, an upwardly tapered circulating column on said chamber, an outwardly flaring spray head thereon having slotted openings in its side walls, and a sheet metal valve member acting to seat within the lower 120 end of said head, said valve when raised being spaced from the walls of said head to direct the fluid toward said openings.

5. In a wash boiler an upwardly extending circulating column, a spray head thereon having outwardly flaring walls with dis- 125

- charge openings therein, a cylindrieal upper end on said head, a valve shaped to approximately fit the inner walls of said head, and adapted when lifted to expose said openings 5 and direct the fluid thereto.
6. In a wash boiler an upwardly directed circulating column, a flaring spray head thereon having discharge openings therein, and means to close said openings responsive to 10 fluid pressure in said column to open and allow discharge of fluid.
7. In a wash boiler a circulating column, a spray head thereon having discharge openings therein, and a valve closing said openings, but adapted to be raised to expose said 15 openings under a required fluid pressure in said colmun.

In testimony whereof I hereunto affix my signature this 23rd day of September A. D. 1926.

DANIEL A. HEGARTY.
